UNITED STATES PATENT OFFICE

151,211

DESIGN FOR A SOAP DISH

Joseph W. Bradbury, Bridgeport, Conn.

Application October 25, 1946, Serial No. 134,238

Term of patent 3½ years

(Cl. D4—3)

To all whom it may concern:

Be it known that I, Joseph W. Bradbury, a citizen of the United States of America, residing at Bridgeport, in the county of Fairfield and State of Connecticut, have invented a new, original, and ornamental Design for Soap Dish, of which the following is a specification, reference being had to the accompanying drawing, forming part thereof.

I claim:

The ornamental design for a soap dish, as shown.

JOSEPH W. BRADBURY.
